UNITED STATES PATENT OFFICE

ARTHUR E. SMALL, OF CHICAGO, ILLINOIS, ASSIGNOR TO P. H. MURPHY COMPANY,
OF NEW KENSINGTON, PENNSYLVANIA, A CORPORATION OF PENNSYLVANIA

CAR-ROOF CONSTRUCTION

Application filed June 25, 1927. Serial No. 201,439.

This invention relates to roofs for railway freight cars, and more particularly to arranging the roof structure to accommodate load lifting devices, both by providing means for attaching such load lifting devices there-to and by designing such roof structures to sustain normal loads upon such load lifting devices without damage to the roof, and has for its further object to provide a roof in

10 which the roof sheets are not deflected or distorted when certain of the carlines are deflected (permanently or otherwise) under excessive stresses caused by a load on a load lifting device; in other words, to provide a roof 15 wherein the carlines may deflect vertically independently of the roof sheets.

Another object of the invention is to provide exterior carlines (integral with the roof sheets or otherwise) which normally cooperate with interior carlines to support the weight of the roof sheets, the snow and slush thereon, and the running boards and also to resist the weaving and buckling stresses always present in a railway car. Such carlines, 25 however, are not secured or attached to each other and are supported by the side plates independently of each other so that the interior carlines may deflect independently of the exterior carlines.

30 Another object is to position an interior carline within an exterior carline so as to obtain a smooth interior roof surface.

It has become customary to arrange the roof or roof framing of a car to accommodate 35 load lifting devices, which devices are not only used to support a load within the car, but are also used to load or unload a car. Such devices are used, for instance, to double deck automobiles and to move heavy machinery 40 about within the car. It has been proposed to provide additional carlines within the car and to reinforce certain carlines within the car and also it has been proposed to provide longitudinal beams within the car which are secured to and supported by the carlines. My 45 device is an improvement on such arrangements in that an excessive load causing a deflection of the carlines does not distort the roof sheets and cause a leaky roof.

50 Some freight car roofs comprise metallic

roof sheets rigidly secured together making what is known as a rigid steel roof, while other roofs comprise roofing sheets which are capable of moving relative to each other and relative to the superstructure of the car 35 as well as relative to the carlines, which roofs are known as flexible all steel roofs. My improvement is adaptable to either rigid or flexible types of car roofs.

In the drawings:

Fig. 1 is a fragmentary perspective of a roof of a car including my invention.

Fig. 2 shows in section the relation of a side plate and interior and exterior carlines.

Fig. 3 is a longitudinal section of the roof 65 shown in Fig. 1.

Fig. 4 shows a modified construction.

Fig. 5 is a longitudinal section along the center line of a flexible roof.

Fig. 6 is a section through the embossment 70 and roof sheet adjacent the side plate.

The construction shown in Figs. 1, 2 and 3 comprises roof sheets 2 spanning the distance between the oppositely disposed side plates 3 of the car which have upstanding 75 flanges 4 at their adjacent marginal portions which are formed and secured together to constitute integral exterior carlines 5, which carlines span the distance between the oppositely disposed side plates of the car and preferably rest thereon. These exterior carlines 80 embrace or surround interior carlines 6 which also span the distance between the oppositely disposed side plates of the car and are secured thereto independently of the exterior carlines. The integral exterior carline 5 and the roof sheet 2 lap over side plate 3 and are secured thereto by rivets 7, while the interior carline 6 rests upon and is secured to the bracket 8 which is secured to the side 85 plate. (See Fig. 2.)

These interior carlines 6 are arranged for attachment of a load lifting device (9), such as ice tongs or hooks which engage the oppositely disposed lower flanges 10 of the 90 interior carline or the interior carline may be provided with apertures to accommodate ropes or chains.

The interior carlines 6 are not secured or attached to the roof sheets 2 or to the ex- 100

terior carlines 5 so that if a load lifting device is attached to the interior carlines and an excessive load applied thereto, the interior carlines may deflect without distorting or deflecting the roof sheets or the exterior carlines whereby the roof proper is maintained in a waterproof and weatherproof condition and it is also still capable of withstanding the weaving and torsional stresses always present in a freight car in running service.

10 The exterior carlines are made of sufficient strength to sustain the ordinary loads on a car roof such as snow, slush and the weight of the running board as well as the weight of the man thereon. These interior carlines normally assist in supporting the roof sheet and any vertical load on the exterior of the roof would be supported by both the interior and exterior carlines. The interior and exterior carlines act independently to resist the torsional and weaving stresses caused by the rocking and swaying of the car.

15 In Fig. 4 I have shown the device as applied to a rigid type of car roof wherein the roof sheets 31 are rigidly secured to each other at their adjacent margins and also rigidly secured to the carline or carline cap 11. The interior carline 12 may be placed midway between the rigid exterior carlines and may be surrounded by an embossment 13 similar to the exterior carline illustrated in Figs. 1, 2 and 3.

20 In Fig. 5 I have shown my improvement applied to a flexible type of steel roof wherein the adjacent sides of the roof sheets 20 are spaced apart from each other and also spaced apart from the carline 21 and a transverse cap 22 is used to waterproof the joint between the adjacent roof sheets. If a load lifting device should be attached to this carline (21) any deflection thereof would also cause a deflection of the transverse cap (22) and also possibly bend or crimp the edges of the upstanding flanges (23) of the roof sheets, thus permitting rain and snow to be driven into the car. The interior carline 24 comprises an inverted U section with a bracket 25 riveted therein for attachment of a load lifting device 26. The roof sheet has an upstanding embossment 27 formed therein which embraces or surrounds the interior carline 24.

25 In this arrangement the rigid carlines hold the roof sheets down against their tendency to jump up due to the impact of coupling the cars and starting or stopping the train.

30 In car construction it is preferable to have the interior surface 30 of the roof as smooth as possible so as not to interfere with the lading, therefore, I position the bottom of the interior carlines not lower than the plane of the roof sheets or substantially flush therewith.

35 The embossments 13 or 27 may be formed

to loosely fit the interior carline to restrict the bodily movement of the roof sheet longitudinally of the car. In flexible roofs these embossments 13 or 27 may vary in width so as to loosely fit or engage the interior carlines adjacent the middle of the car only, which would not only restrict the bodily movement of the roof sheet longitudinally of the car, but would permit or allow the roof sheets to pivot or swing around such place of engagement, in a substantially horizontal plane; i.e., in the planes of the apaxed roof which are substantially horizontal.

40 The accompanying drawings illustrate the preferred form of the invention, though it is to be understood that the invention is not limited to the exact details of construction shown and described, as it is obvious that various modifications thereof within the scope of the claims will occur to persons skilled in the art.

I claim:

1. In a railway car roof; a plurality of roof sheets and a plurality of carlines, some of said carlines being rigidly secured to said sheets and other of said carlines being free to deflect downwardly independently of the roof sheets, said last mentioned carlines being formed to accommodate a load lifting device.

2. In a railway car roof; a plurality of roof sheets and a plurality of carlines, some of said carlines being rigidly secured to said sheets and other of said carlines being free to deflect downwardly independently of the roof sheets and the first mentioned carlines, said last mentioned carlines being formed to accommodate a load lifting device.

3. In a railway car roof; a plurality of roof sheets and a plurality of carlines, some of said carlines being arranged to restrict the upward movement of said sheets and other of said carlines being free to deflect downwardly independently of the roof sheets, said last mentioned carlines being formed to accommodate a load lifting device.

4. In a railway car roof; a plurality of roof sheets and a plurality of carlines, some of said carlines being positioned above said roof sheets and rigidly secured thereto and other of said carlines being positioned below said roof sheets and free to deflect downwardly independently of the roof sheets, said last mentioned carlines being formed to accommodate a load lifting device.

5. In a railway car roof; a plurality of roof sheets and a plurality of carlines, some of said carlines being rigidly secured to said sheets and other of said carlines being free to deflect downwardly independently of the roof sheets, said other carlines provided with oppositely disposed flanges spaced apart from the roof sheets so as to provide means for attachment of a load lifting device.

6. In a railway car roof; a plurality of roof sheets and a plurality of carlines, some

of said carlines being rigidly secured to said sheets and other of said carlines being free to deflect downwardly independently of the roof sheets, said other carlines provided with oppositely disposed flanges not lower than the plane of the roof sheets and spaced apart therefrom so as to provide means for attachment of a load lifting device.
